UNITED STATES PATENT OFFICE.

JESSE L. DELANO, OF NORTHAMPTON, MASSACHUSETTS.

REVERSIBLE PLOW.

SPECIFICATION forming part of Letters Patent No. 312,438, dated February 17, 1885.

Application filed June 5, 1884. (No model.)

To all whom it may concern:

Be it known that I, JESSE L. DELANO, of Northampton, in the county of Hampshire and State of Massachusetts, have invented a new and useful Improvement in Reversible Plows, of which the following is a full, clear, and exact description.

My improvements relate to plows having revolving mold-boards, the object being to obtain a construction that allows reversing of the mold-board with greater ease than with plows as heretofore made, and that can be manufactured with greater facility.

The essential features of the invention consist in the point made separately from the mold-board and hung to swing on a horizontal axis, and a double-sided mold-board swinging on a vertical axis, as hereinafter described and claimed.

Reference is to be had to the accompanying drawings, forming a part of this specification, in which similar letters of reference indicate corresponding parts in all the figures.

Figure 1 is a plan view of the improved plow. Fig. 2 is a side elevation with the mold-board partly broken away. Fig. 3 is a cross-section on line *xx* of Fig. 2, and Fig. 4 is a front view of the plow as arranged to turn a furrow both ways.

The beam *a* is provided with a rear standard, *b*, that gives support to the gearing that operates the movable mold-board and point. The mold board *A* is formed double, or alike on either side, and at the angle of its forward end is hung by pivots *c* to a vertical post, *d*, depending from the beam *a*. The point *B* is shaped at its rear end to coincide with one half the end of board *A*, and is attached rigidly to a horizontal bar, *f*, which is hung in eyes *e* at the lower ends of standard *b* and post *d*, so that it passes beneath the mold-board. To bar *f* is swiveled an arm, *g*, extending up into the hollow center of the mold-board and entering a tubular rod, *h*, that is swiveled to a fixture on the board *A*, so that when the mold-board is swung to right or left the bar *f* and point *B* are rocked.

For shifting the board and point right and left, I provide a vertical shaft, *i*, which is sustained by beam *a* and standard *b*, and has a horizontal arm, *k*, with an eye at its outer end, engaging a slide-rod, *l*, attached upon the mold-board. The shaft *i* has handles for its

convenient operation to swing the mold-board to its right or left position and turn the point over upon its axis. Only a slight movement of the shaft *i* is required to shift the plow, and the parts work easily. The point is provided with spring-catches *m*, that take behind the post *d* and beneath the edge of the mold-board so as to lock the parts together.

Any suitable means may be employed to shift the plow. I do not limit myself in that respect, nor to a mold-board of any special shape, as it is evident the shape may be varied. The advantages of this construction are, that the parts of the plow can be readily manufactured, and are not expensive, and the operation of shifting being easy removes a great objection to this class of plows as heretofore made.

By placing and securing the parts in a midway position, as shown in Fig. 4, the plow will turn a furrow both ways.

Having thus described my invention, what I claim as new, and desire to secure by Letters Patent, is—

1. In a reversible plow, the point *B*, with its lower edge in line with its apex, pivoted to swing upon a horizontal axis, in combination with the mold-board *A*, of an approximately **A** shape, pivoted centrally of its length to swing horizontally upon a vertical axis, whereby the point and board are adapted to turn the earth either to the right or the left, or to turn it both ways, substantially as described.

2. The combination, in a plow, of hinged mold-board *A*, post *d*, hinged point *B*, and horizontal bar *f*, said point being fixed to said bar at its apex, and said bar being connected to the mold-board by a swiveled telescopic connection, together with means to shift the mold-board, substantially as shown and described.

3. The combination of point *B*, mold-board *A*, rock-bar *f*, arm *g*, and tubular rod *h*, substantially as described.

4. The combination, with point *B* and mold-board *A*, connected for simultaneous reversal, of shaft *i*, arm *k*, and slide-rod *l*, substantially as described.

JESSE L. DELANO.
